DESIGN FOR A DRESS

Margaret Michelson, New York, N. Y.

Application December 9, 1938, Serial No. 81,681

Term of patent 3½ years

To all whom it may concern:

Be it known that I, Margaret Michelson, a citizen of the United States, residing at 525 Seventh Avenue, New York, in the county of New York and State of New York, have invented a new, original, and ornamental Design for a Dress, of which the following is a specification, reference being had to the accompanying drawing, forming part thereof.

Fig. 1 is the front view of a dress showing my design.

Fig. 2 is a rear view thereof.

The characteristic feature of my design resides in the combination on the specific shirtwaist dress disclosed of the blouse section which is decorated by narrow bands of lace edging stitched down on their upper edges and arranged in close relationship on a horizontal plane, in association with the plain untrimmed skirt as shown.

I claim:

The ornamental design for a dress, substantially as shown and described.

MARGARET MICHELSON.
